(Cl. D3—4)

Figure 1 is a front perspective view of a sweater or similar article showing my new design; and

Figure 2 is an enlarged fragmentary view of the portion indicated at 2 in Figure 1.

The decorative open-work areas beneath the collar are like the uncovered open-work areas on the front and the undecorated portions of the sweater are of a conventional knit as fragmentarily depicted in Figure 2. The back of the sweater or similar article is plain and unornamented.

I claim:

The ornamental design for a sweater or similar article, substantially as shown and described.
